(57) **CLAIM**

We claim the monocoque frame for a treadmill, as shown and described.

DESCRIPTION

FIG. 1 is a perspective view;

FIG. 2 is a front elevational view;

FIG. 3 is a rear elevational view;

FIG. 4 is a left side elevational view;

FIG. 5 is a right side elevational view;

FIG. 6 is a top plan view thereof; and,

FIG. 7 is a bottom plan view thereof.

The broken lines showing of the treadmill structure is for illustrative purposes only and forms no part of the claimed design.
